Elmer Nickerson

Attorney

UNITED STATES PATENT OFFICE.

ELMER NICKERSON, OF OUTLOOK, MONTANA.

WRENCH.

Application filed November 16, 1925. Serial No. 69,421.

This invention relates to new and useful improvements in wrenches, and particularly to sliding jaw wrenches.

One object of the invention is to provide a wrench wherein the movable jaw has slideable and pivotal movement to more properly and firmly grip the work, and wherein such movable jaw is normally and resiliently held away from the shank of the wrench, whereby to quickly and easily release itself from the work, to obtain a new grip on such work.

Another object is to provide a moving means for the slideable jaw which is actuated by hand, against a spring means which also serves to urge the jaw toward normal position.

Another object is to provide, in addition to the manually actuated spring held means, a spring means for normally urging the jaw member away from the shank of the wrench, and in counteraction against the first spring means.

Other objects and advantages will be apparent from the following description when taken in connection with the accompanying drawing.

In the drawing:

Figure 1 is a side elevation of a wrench made in accordance with the present invention.

Figure 2 is a bottom plan view of the same.

Figure 3 is a sectional view on the line 3—3 of Figure 2.

Figure 4 is a transverse sectional view on the line 4—4 of Figure 1.

Referring particularly to the accompanying drawing, 10 represents the shank of the wrench which has the series of ratchet teeth 11 formed in its back edge. In the other edge of the shank there is formed a longitudinal groove 12, which extends from the rigid jaw 13, at the outer end of the shank, to a point adjacent the handle portion 10', of the shank. Disposed within this groove is the thinner portion 14' of the movable jaw member 14, the thicker portion of which is limited in its movement in one direction by contact with the adjacent edge face of the shank. In the outer face of the jaw member 14 there is formed a longitudinal groove 15 in which is seated an end portion of a leaf spring 16, to which reference will be

made later herein. Fixed in a notch 17, 55 in the thinner portion of the jaw member 14 is one end of a leaf spring 18, the other or free end of which bears against the bottom of the groove 12, of the shank, whereby to normally and yieldably urge the jaw member 60 away from the shank.

Slidably embracing the shank 10 is a block 19, and formed longitudinally in the shank, beneath the block, is a slot 20. Disposed through the block, the slot, and the 65 thinner portion of the jaw member, is a pivot member 21, on which said block and jaw member are adapted to swing.

When the jaws are engaged with a piece of work, and the wrench manipulated in 70 the proper manner, the jaw member 14 will swing inwardly toward the shank 10, so that the leaf spring 18 will be compressed. Upon manipulating the wrench to obtain a new grip on the work, the spring 18 will move 75 the jaw member outwardly, thus permitting release of the wrench from the work, if desired.

The tendency of the leaf spring 16, whose 80 other end is secured to the rockable block 19, is to rock the block and cause its teeth 22 to engage with the teeth 11 of the shank 10, whereby said block is held against movement away from the rigid jaw. This spring also has a tendency to swing the jaw member 85 14 inwardly toward the shank, but such action is counteracted or counterbalanced by the spring 18.

The back portion of the block, or that portion which rides over the teeth 11, is provided with a rearwardly extending handle member or fingerpiece 23, which is arranged to be depressed by the thumb or finger of the operator, to rock the block 19 so as to disengage its teeth 22 from the teeth 11, 90 and thereby permit the free sliding of the block longitudinally of the shank. The jaw member 14 being connected with the block 19 by means of the pivot 21, moves longitudinally of the shank, with the block, 95 whereby to position the jaw member at the proper distance from the rigid jaw to accommodate the work therebetween.

It will be noted that the pivotal end of 100 the jaw member 14 is formed with a projecting heel 24 which is arranged to engage with the bottom wall of the groove 12 of the block 19, whereby to prevent too great

outward swinging movement of said jaw, which might tend to break or excessively bend the spring 16.

What is claimed is:

- 5 1. A wrench including a toothed shank having an outer rigid jaw, an inner jaw slidably and pivotally supported within the shank, a rockable member straddling the shank and being pivoted coincident with the 10 inner jaw for slidable movement therewith but independent pivotal movement, said rockable member being arranged to interlock with the toothed shank, a spring means carried by the rockable member and engaging with the inner jaw for yieldably holding the rockable member engaged with the shank, and a spring means between the inner jaw and the interior of the shank for normally rocking said inner jaw out of the 15 shank.
- 20 2. A wrench including a shank having teeth and an outer rigid jaw, an inner jaw slidably seated in said shank, the shank having a longitudinal slot, a block straddling the shank and inner jaw, a pivot disposed through said slot to permit simultaneous sliding of the jaw and block and independent pivotal movement thereof, there being teeth on the block for engagement with the 25 teeth of the shank, a spring carried by the block and engaging with the inner jaw for normally urging the teeth of the block into engagement with the teeth of the shank, and a spring carried by the inner jaw and engaged with the shank for rocking the said 30 inner jaw on its pivot away from the shank.
- 35 3. A wrench including a shank having teeth on one of its edge faces and a groove longitudinally in its other edge face, a jaw member having a shank portion slidably seated in said groove, said shank having a longitudinal slot, a block embracing the shank, a pivot disposed through the said slot and connected to the shank of said jaw member, there being teeth on the said block 40 engaged with the shank teeth, a leaf spring secured at one end to the block and having its free end engaged with the jaw member, and a spring carried by the said jaw member and engaged with the shank of the 45 wrench in said groove for urging the jaw member outwardly away from the said shank.
- 50 4. A wrench including a shank having teeth on one of its edge faces and a longitudinal slot, a jaw member slidably mounted on the shank, a slideable block embracing the shank and a portion of the jaw member, a pivot disposed transversely through the slot, through the block, and through the jaw 55 member, whereby to permit simultaneous sliding movement of the jaw and block and independent pivotal movement thereof, there being teeth on the said block engaged with the shank teeth, a spring secured at one end to the block and having its free end engaged with the jaw member, and a spring secured at one end to the jaw member and having its 60 free end engaged with the shank.

In testimony whereof, I affix my signature.

ELMER NICKERSON.
